[57] **CLAIM**

The ornamental design for a transparency viewer, substantially as shown.

DESCRIPTION

FIG. 1 is a front elevational view of a transparency viewer showing my new design;

FIG. 2 is a rear elevational view thereof;

FIG. 3 is a right side elevational view thereof;

FIG. 4 is a left side elevational view thereof;

FIG. 5 is a right front perspective view thereof.
The power cord is shown abbreviated in FIGS. 1-3 and 5 for ease of illustration.

FIG. 1

FIG. 2

FIG. 3

FIG. 4
